UNITED STATES PATENT OFFICE.

RYERSON D. GATES, OF CHICAGO, ILLINOIS.

STONE-BREAKING AND ORE-CRUSHING MACHINE.

SPECIFICATION forming part of Letters Patent No. 251,040, dated December 20, 1881.

Application filed September 7, 1881. (No model.)

To all whom it may concern:

Be it known that I, RYERSON D. GATES, a citizen of the United States, residing at Chicago, in the county of Cook and State of Illinois, have invented a new and useful Improvement in Stone-Breaking and Ore-Crushing Machines, of which the following is a specification.

My invention relates specially to an improvement in the conical crusher-head which is applied to the upright crusher-shaft of stone breakers and crushers, but may be applied to other styles of crusher-heads; and the nature of my invention consists, first, in a crusher-head wherein hard-metal sections provided with tongues and recesses adapted to the form of clamping-bolts are combined with a flanged base portion provided with depressions and recesses, also adapted to the form of clamping-bolts, and a cap and clamping-bolts, as will be hereinafter described; second, in the combination of a crusher-shaft base portion provided with depressions and recesses, with hard-metal sections having tongues and depressions, a beveled cap, and clamping-bolts, as will be hereinafter described.

The crushing-head of stone-breaking machines such as that shown in Letters Patent No. 243,545 has heretofore been cast in one solid hard-metal piece, and then fastened to the shaft by means of zinc run between the head and shaft; and when the head is worn out and it requires to be renewed, or when it is desired to put on a larger or smaller head in order to crush finer or coarser, it is usually necessary 30 to take the shaft entirely out of the machine, turn it upside down, bury the crusher-head in the ground, build and keep a fire around it until the zinc which fastens the head to the shaft is melted, then take off the head, put on the new 35 or larger or smaller one, true it up, fasten it with zinc, and then replace the shaft and head in the stone-breaker. This operation is very bothersome, and in cases where the shaft and head weigh four thousand five hundred pounds 40 it takes a great deal of time and labor, which involves considerable expense, and nearly all of which my improvement avoids.

In the accompanying drawings, Figure 1 is a vertical central section of the upper portion 45 of a stone-breaker with my improvement applied to it. Fig. 2 is a horizontal section of the improved crusher-head in the line xx of Fig. 1;

and Fig. 3 is a perspective view of one of the segments of the working-face of the crusher-head and of one of the clamping-bolts, the latter being out of its position. Fig. 4 is a broken section of the base portion of the crusher-head. Fig. 5 is a perspective view of the base portion of the crusher-head, showing one of a series of recesses which are to be formed in said base portion.

A is an ordinary shaft of a crusher-head. It has, as usual, a polygonal form in horizontal section at the line xx , and is provided with grooves a for the reception of zinc, which is flowed into the grooves for the purpose of fastening the crusher-head to the shaft.

B and C represent my improved crusher-head, applied and fastened to the shaft A by zinc rings b . The part B has grooves a' formed in it at points opposite the grooves a of the shaft, and the fluid zinc is flowed into these grooves in the ordinary manner and allowed to become "set." The said part B is what I term a "false" head or base, and it is made of soft or other suitable metal, and it is not to be removed from the shaft when the working or face portions C are removed for any cause. This part B is in form of a hollow pyramid, and is provided with a broad circular flange, c , at its bottom; and in its flat tapering sides are tapering grooves or depressions d , having beveled bottoms e , as shown. The depressions d are inclined or vanishing at their front edges and straight on their backs—that is, their back surfaces are parallel with the axis of the shaft A, while their front edges are on lines corresponding with the tapering sides of the pyramidal part B, and in these back surfaces recesses d' , corresponding respectively to the form of one-half of the body and head of a bolt, D, are formed. The depressions d vanish, so as to have no depth beyond the recesses for the screw-bolts, in terminating at the top of the pyramidal part B.

The portion C of the crusher-head consists of a number of segmental pieces of hard or chilled metal. The outer surfaces of these pieces are segments of circles, and these surfaces are corrugated, and the inner surfaces or back sides of said pieces are flat, except at the places where tapering and recessed tongues f are formed on them, as shown. The flat surfaces and tongues f of the pieces correspond

substantially with the flat surfaces and depressions d d' of the pyramidal part B of the crusher-head, and thus when the pieces C are made to form a circle around the part B their radial edges g will adjoin, while their flat back surfaces and their tongues match the flat sides and depressions of the part B, and the recesses of the tongues partly receive the bodies and heads of the bolts D into them, as illustrated 10 in the drawings.

The meeting surfaces of the portions B and C may be "backed up" with zinc or Babbitt metal, as at g' , if deemed necessary.

E is a circular cap, made flat, as at h , and flaring and concave, as at h' , on its under side, in order to fit the horizontal end of the part B and the beveled upper ends, h^2 , of the segmental pieces C, as shown. This cap has an opening in its center, which allows it to pass over 15 the shaft, and it also has holes in it, which allow it to pass down over the screws. By adjusting this cap over the shaft and screw-bolts and down upon the portions B and C, and then screwing down nuts i upon the ends of the 20 bolts, the segments C will be firmly held in place upon the part B. By simply removing the cap E the segments can be removed and others substituted for them, the removal of the part B and shaft A from the machine being 25 wholly unnecessary. The heads of the bolts, where they enter the tongues of the segments C, are partly cut away in order to avoid weakening the segments.

I have represented in the drawings an adjustable concave; but the same is not claimed under this application, but will form the subject-matter of another patent applied for by me.

The base portion B, with grooves and recesses in its outer surface, might be cast, with 30 the shaft A, out of steel, or even good iron, without materially departing from my invention, and without destroying its utility for crushing some materials; and instead of uniting the base portion B to the shaft A by rings of zinc 35 flowed in between it and the shaft A, the base portion might be united to the shaft by means of a key or pin passed through the shaft at top of crusher-head; or it might be fastened to the shaft in various ways without departing from 40 my invention.

Previous to my invention the grinding and breaking surfaces of meal, bone, bark, and cob or grain mills have been constructed in detachable parts and applied upon or against a base-support, but in such constructions the parts 55 were not formed and united so as to be practically adapted for the hard work of breaking stone and crushing ore; and the improvements which I have made in such constructions have special reference to the performance of such 60 work, and to that end I have made the base or foundation portion B of the head with the peculiar formation of recesses shown in the drawings, and formed on the segmental sections of crushing-surface of the head peculiar 65 projections for fitting said recesses, and, in addition to the recesses and tongues, I have provided partly-headed binding-bolts and a clamping-cap, which, in conjunction with bottom rests for the segmental sections, serve as means 70 whereby the several parts of the crusher-head can be united almost as firmly and compactly as one solid mass, and yet can at will be separated for the purposes set forth in my foregoing specification.

What I claim as my invention, and desire to secure by Letters Patent, is—

1. In a crusher-head for stone and ore crushing machines, the combination of the hard-metal sections C, provided with the tongues f and recesses adapted to the form of the clamping-bolts, with the flanged base portion B, provided with depressions d' and recesses d , also adapted to the form of the clamping-bolts, the cap E, and clamping-bolts D, substantially as 80 85 and for the purpose described.

2. The combination of crusher-shaft A, base portion B, provided with depressions d' and recesses d , with segmental hard-metal sections C, having tongues f and depressions adapted 90 to the form of the clamping-bolts, cap E, beveled on its under side, and clamping-bolts D, substantially as and for the purpose described.

RYERSON D. GATES.
